UNITED STATES PATENT OFFICE.

CHARLES S. VAN NUIS, OF NEW BRUNSWICK, NEW JERSEY.

ELECTRIC-ARC LAMP.

SPECIFICATION forming part of Letters Patent No. 591,026, dated October 5, 1897.

Application filed May 1, 1896. Serial No. 589,924. (No model.)

To all whom it may concern:

Be it known that I, CHARLES S. VAN NUIS, a citizen of the United States, residing at New Brunswick, in the county of Middlesex and State of New Jersey, have invented a certain new and useful Improvement in Electric-Arc Lamps, of which the following is a specification.

My invention relates to the transparent or translucent globes employed in electric-arc lamps for inclosing the arc to increase the life of the carbons and has special reference to the manner in which such globes are supported and the means for preventing the entrance of air to the inclosing globe and the escape of gases from within the same, and to means for permitting the automatic adjustment of the globe.

My invention is illustrated in the accompanying drawings, in which—

Fig. 1 is an elevation of an arc-lamp with my improved inclosing globe applied thereto. Fig. 2 is a central section, on an enlarged scale, of a cap for the top of the globe, through which the positive carbon passes; and Fig. 3 is a central section and partial elevation, on an enlarged scale, of the negative carbon, the collar at the lower end of the inclosing globe, and the base upon which this collar rests.

Referring to the drawings, A and B represent the positive and negative carbons, respectively, of any form of arc-lamp, and C the transparent or translucent inclosing globe. At the top of this globe is placed a cap D, containing a number of chambers, three being shown and marked d' , d^2 , and d^3 . These chambers are preferably formed by constructing the cap in several circular cup-shaped parts having flanges d^4 , to which the successive parts forming the cap are screwed, as illustrated in Fig. 2. The top of each section of the cap is provided with a vent-hole x , which is normally closed by any suitable form of valve, a ball x' being shown and contained within a perforated shell x^2 . Each section of the cap is also provided with a central opening y , through which the carbon A passes, and these openings are of such diameter that the carbon A will fit as tightly as is consistent with the proper feeding of the carbon, the object of the close fit being to make

the cap as air-tight as practicable to prevent the entrance of air into the inclosing globe C.

The inclosing globe C at its bottom is provided with a neck c , which is inserted in a collar E and made air-tight by a packing e , of asbestos or other heat-resisting material, and the collar E is clamped to the neck c by several screws e' . The collar E is provided with a bottom e^2 , having a central opening e^3 of such diameter as to allow the holder of the carbon B to pass therethrough with considerable clearance. The lower end of the collar E is provided with a circular flange e^4 , whose inner surface e^5 is concaved, and this concaved surface fits closely upon a circular base F, having a convex periphery of such curvature as to form a close and practically air-tight joint with the concave surface e^5 of the flange e^4 . These two surfaces are preferably ground together to make a true and tight-fitting joint. This base F is carried by the carbon-holder B' and, if desired, may be made integral therewith. It will be seen that the base F and flange e^4 form a ball-and-socket joint, which permits the movement of the globe C, while at the same time maintaining a practically air-tight joint. This form of base for the globe C permits of a very close-fitting base D, through which the carbon A passes, and if for any reason the carbon A should move out of its longitudinal center or should there be any tendency of the carbon to bind from any cause the globe C is free to move with it, thus preventing or greatly reducing any binding action between that carbon and the cap D.

The object of providing the cap with the several chambers d' , &c., is to dilute the air which may enter with the gases that escape from the globe C, and thus prevent the entrance of air into the inclosing globe C. To make this more clear, let it be supposed that the gases formed within the globe C escape around the carbon A through the opening y and through opening x of section d of the cap into the first chamber d' . The gases will become diluted with the air in that chamber, and the diluted gases escaping from chamber d' into chamber d^2 will become diluted with the air therein, the resulting mixture of air and gases being less dense than that in chamber d' . The

diluted gases escaping from chamber d^2 into chamber d^3 will become diluted with the air therein, and the resulting mixture of air and gases will be less dense than that in chamber 5 d^2 . Thus it will be seen that the air entering the chambers becomes so diluted with the gases therein that practically no air will enter the globe C. The valves x' are provided to permit the escape of the gases first from 10 the inclosing globe C and then from the chambers d' , &c., when the pressure becomes too high.

What I claim is—

1. In an arc-lamp, the combination with the 15 carbons, of an inclosing globe for the arc, having an aperture through which a carbon passes with a practically air-tight fit, and an adjustable and practically air-tight joint for said globe where the other carbon enters and 20 whereby the globe is free to adjust itself relative to the carbons while maintaining said last-named joint air-tight, substantially as set forth.

2. In an arc-lamp, the combination with the 25 carbons, of an inclosing globe for the arc, having an aperture through which a carbon passes with a practically air-tight fit, and a practically air-tight ball-and-socket joint for said globe where the other carbon enters and 30 whereby the globe is free to adjust itself relative to the carbons while maintaining said last-named joint air-tight, substantially as set forth.

3. In an arc-lamp, the combination with the 35 carbons, of an inclosing globe for the arc, having an aperture through which a carbon passes with a practically air-tight fit, a base carried by the lower carbon-holder, and a collar at the lower end of said globe seated on said 40 base to support the globe, said base and collar forming a practically air-tight ball-and-socket joint, which joint permits the globe to adjust itself relative to the carbons while maintaining the joint air-tight, substantially as set 45 forth.

4. In an arc-lamp, the combination with the carbons, of an inclosing globe for the arc, a cap at one end of the globe provided with an aperture through which a carbon passes with a practically air-tight fit, and an adjustable and 50 practically air-tight joint at the other end of the globe where the second carbon enters, and which joint permits the globe to adjust itself relative to the carbons while maintaining the joint air-tight, substantially as set forth. 55

5. In an arc-lamp, the combination with the carbons, of an inclosing globe for the arc having two or more chambers at one end thereof, and provided with apertures through which a carbon passes with a practically air-tight 60 fit, a valve for permitting the escape of gas from the inclosing globe into the adjacent chamber when the pressure becomes too high, and valves for each chamber permitting the escape of gas to successive chambers and to 65 the exterior of the last chamber, substantially as set forth.

6. In an arc-lamp, the combination with the carbons, of an inclosing globe for the arc, a cap for said globe provided with two or more 70 chambers having apertures through which a carbon passes with a practically air-tight fit, and valves for each chamber permitting the escape of gases to successive chambers and to the exterior of the cap, substantially as set 75 forth.

7. In an arc-lamp, the combination with the carbons, of an inclosing globe, and a cap therefor through which one of the carbons passes, said cap consisting of several circular cup-shaped parts screwed together to form separate chambers having central openings in the walls thereof for the carbon, and valves for each chamber, substantially as set forth. 80

This specification signed and witnessed this 85
24th day of April, 1896.
